Primary Examiner — Rhea Shields

(57) **CLAIM**

The ornamental design for a device for control of electric power, as shown and described.

DESCRIPTION

1. Device for control of electric power

1.1: Perspective

1.2: Front

1.3: Back

1.4: Left

1.5: Right

1.6: Top

1.7: Bottom

A device for control of electric power; The device for control of electric power is used for controlling and switching power supplies; The design claims the overall shape of the device; the most representative drawing or photograph is the perspective view of the design.

In the reproductions, the broken lines are for the purpose of illustrating portions of the device for control of electric power that forms no part of the claimed design.
